US00D916616S

(12) **United States Design Patent** (10) **Patent No.:** **US D916,616 S**
(45) **Date of Patent:** **** Apr. 20, 2021**

(54) **OSCILLATING WEIGHT**

(71) Applicant: **Harry Winston SA**, Plan-les-Ouates (CH)

(72) Inventor: **Steve Kamilindi**, Plan-les-Ouates (CH)

(73) Assignee: **Harry Winston SA**, Plan-les-Ouates (CH)

(**) Term: **15 Years**

(21) Appl. No.: **29/699,232**

(22) Filed: **Jul. 24, 2019**

(30) **Foreign Application Priority Data**

Jan. 30, 2019 (WO) DM/200690

(51) **LOC (13) Cl.** **10-07**

(52) **U.S. Cl.** USPC **D10/129**

(58) **Field of Classification Search**
